ELECTRIC CLOCK

José Andrés Hernandez, Habana, Cuba

Application September 28, 1937, Serial No. 166,212

5 Claims. (Cl. 58—26)

This invention relates to electric clocks, and it has for its object to provide an improved clock structure consisting in means associated with its electrically-driven mechanism, which means 5 actuate by gravity and are connected by suitable gear means with one of the clock time indicating shafts, said means being automatically put in action when the electric current in the line that supplies the motor operating the clock falls short 10 to any reason, so that the clock may continue to operate uninterruptedly.

Another object of the invention is to provide a mechanism for releasing the means actuating by gravity, in association with electromagnetic 15 means in shunt relation with the electric motor in the line supplying electric energy to the latter, and which mechanism comes into action automatically when the electric current supplied to the motor fails, so that while the electric current 20 is supplied, said electromagnetic means may retain in locked position said means actuating by gravity, and when the electric current fails, the means actuating by gravity may be released to freely actuate the usual escapement mechanism.

25 A further object of the invention is to provide a mechanism in an electric clock embodying such gravity actuated means which upon the resumption of the electric current supply will automatically return the gravity actuated means 30 to its initial fully raised position.

The invention is described with reference to the figures of the accompanying drawings, of which:

Fig. 1 is a front elevational view, partly cut 35 away, of the frame of an electric clock provided with the improvements constituting the subject-matter of this invention.

Fig. 2 is a rear elevational view of said frame.

Fig. 3 is an upper plan view of the same frame. 40 Fig. 4 is a vertical sectional view on line 4—4 of Fig. 3, looking to the rear portion of the frame, in the operating position of the operating means actuating by gravity.

Fig. 5 is a horizontal view on line 5—5 of Fig. 4, 45 in the operating position of the operating means actuating by gravity.

Fig. 6 is a vertical sectional view similar to that of Fig. 4, in the operating position of the electric means usually operating an electric clock.

50 Fig. 7 is a horizontal sectional view similar to Fig. 5, in the operating position of the electric operating means.

Fig. 8 is a perspective detailed view showing the oscillatable frame for releasing or holding 55 the means actuating by gravity.

Fig. 9 is a perspective detailed view of the slidably mounted weight forming the means actuating by gravity.

Fig. 10 is a partial rear elevational view of the frame of the electric clock, showing the weight 5 actuating by gravity and the gears connected therewith in the position in which the clock operates mechanically.

Fig. 11 is a horizontal sectional view on line 11—11 of Fig. 10.

Fig. 12 is a similar view to Fig. 10, showing the 10 clock when operating electrically.

Fig. 13 is a partial vertical sectional view on line 13—13 of Fig. 7, showing the clutching slid- 15 able shaft for changing from the electric operat- ing means to the mechanical operating means, and vice versa, in the operative position of the electric operating means.

Fig. 14 is a sectional view similar to that of Fig. 13, in the operative position of the mechan- 20 ical operating means.

Fig. 15 is a horizontal section view on line 15—15 of Fig. 6.

Fig. 16 is a side elevational view of the clock showing the side whereon the actuating weight is 25 mounted, in the released position thereof, when it begins to fall.

Fig. 17 is a view similar to that of Fig. 16, showing the weight in falling position, when the electric operating means have been connected 30 again.

In Figs. 1, 2 and 3 of the drawings is illustrated an electric clock the supporting frame of which is formed by two vertical metal plates 1 and 2 disposed parallelly to each other and spaced 35 apart a fixed distance by means of spacing members 3 secured by screws 3' to said plates. On the upper portion of the rear plate 2 is mounted an electric motor 4 whose horizontal driving shaft 5 extends across the plate 2 and ends in 40 the intermediate space between plates 1 and 2 wherein it carries a fixed cylindrical gear wheel 6 meshing with the first gear wheel of a train of cylindrical gear wheels 7, 8 and 9 the horizontal shafts of which are rotatably mounted on an 45 angular supporting arm 10 fixed behind the fore plate 1. Although the shaft 11 of the last gear wheel 9 extends to the other side of the fore plate 1, it is slidably mounted through an opening in the latter and through an opening in the 50 supporting arm 10 for the purpose that will be explained hereinafter.

On the middle portion of the shaft 11 is fixed a cylindrical gear pinion 12 which is adapted to mesh with a cylindrical gear wheel 13 fixed on 55

the middle portion of a horizontal shaft 14 rotatably mounted through openings in the fore plate 1 and rear plate 2 and on which are also fixed a cylindrical gear pinion 15 near the plate 5 1 and behind same and a small cylindrical gear wheel 16 near the plate 2 and behind same. The gear pinion 15 permanently meshes with a big cylindrical gear wheel 17 fixed on the horizontal shaft 18 rotatably mounted through the openings 10 in the plates 1 and 2 and extends beyond the front of plate 1 whereat it carries the hands 19 and 20 on a dial not shown, so that the shaft 18 will hereinafter in this description be termed "time indicating shaft." The description so far 15 given herein is that of the structure of a usual electric clock.

This invention has for an object to provide mechanical means for actuating the time indicating shaft 18 upon failure of the current flowing in the electric line supplying power to the electric motor 4. Such mechanical means actuate by gravity and consist of a heavy metallic weight 21 slidably mounted by means of an angular groove 22 which it carries longitudinally 20 on a slidable guide consisting of an angular flange 23 formed at the adjacent side of the rear plate 2, the flange 23 being complementary to flange 22 so that upon being engaged together they close completely one upon the other, and 25 the weight 21 carries on its fore face an oblique-toothed rack 24 with one of whose teeth is adapted to engage a pawl 25 formed at the end of a spring 26 fixed at the other end thereof by means of screws 27 on the inner face of the plate 2.

Normally the weight 21 is held in fixed position by said pawl 25, but immediately as current ceases to be fed to the electric motor 4, said pawl 25 is withdrawn from the rack 24 by means of a straight cam boss 28 formed on the face of a 40 metallic strip 29 slidably mounted by means of a pair of vertical slots 30 formed therein on a pair of screws 31 horizontally fixed at vertically spaced points on the inner face of the plate 2.

Said strip 29 is pivotally connected at its 45 upper end by means of a horizontal pin 32 with the lower end of a connecting link 33 which is pivotally connected at its upper end by means of a horizontal pin 34 with a supporting arm 35 projecting from the end of an oscillatable frame 36 oscillatorily mounted within the space between the plates 1 and 2 on a horizontal pivot axis 37 supported on plates 1 and 2. Said frame 36 is pivotally connected by means of a horizontal pin 38 passing through an opening in a lug 39 projecting upwards from an intermediate portion 45 of said frame 36, with the end of the forked lower portion of the movable armature 41 of an electromagnet 42 mounted on the top of plates 1 and 2 and which is connected in parallel with the electric motor 4 in the circuit formed by electric conductors 43 and 44 supplying electric current to the motor 4 from any suitable source of supply which will generally be the electric light line for a city or town.

Said oscillatable frame 36 carries on the middle portion of its side adjacent the plate 2 a downward lug 45 on which is fixed by rivets 46 a downward sheet spring 47 precisely behind the rear end of the slidably mounted shaft 11.

In this manner, the shaft 11 will be engaged by the curved lower portion of the spring 47, when the latter descends carried by the oscillatable frame 36 (see Fig. 13) and said shaft 11 will be caused to run to the front until its fore 75 end strikes against another sheet spring 48 fixed

by rivets 49 on the fore face of plate 1 to be held in a position in which the gear pinion 12 does not mesh with the gear wheel 13 on the shaft 14 forming part of the gear mechanism transmitting motion from the electric motor 4 to the time marking shaft 18. Said oscillatable frame 36 carries also in cross alignment between the spring 47 and its end connected to the link 33, two downward arms 50 on the lower ends of which is mounted through openings therein a horizontal counter-shaft 51 carrying a cylindrical gear pinion 52 adapted to mesh with the gear wheel 13 and a cylindrical gear wheel 53 adapted to mesh with a small cylindrical gear wheel 54 forming part of the usual escapement mechanism 15 in clocks and which is mounted within a casing 55 fixed to the plate 1 at its side opposite the heavy weight 21 and which is designed to control the operation of the clock marking shaft 18 when the action of the electric motor 4 ceases. 20 The downward movement of the oscillatable frame 36 is limited by a pin 36' fixed to the plates 1 and 2.

It is to be understood that the casing 55 encloses a clock escapement but not a clock movement. 25

The heavy weight 21 carries on its side adjacent the rear face of the plate 2 a vertical rack of straight teeth 56 (Figs. 10, 14, 15 and 16) with which permanently meshes a cylindrical gear wheel 57 the bushing 58 of which is idle on a horizontal spindle 59 threaded to the plate 2, and with the bushing 58 is made integral a ratchet wheel 60 with one of which teeth engages a pawl 61 pivotally mounted by a horizontal pin 35 62 on the fore face of a cylindrical gear wheel 63 the bushing 64 of which is idle on the same horizontal shaft 59, the bushings 58 and 64 being held on the shaft 59 by means of a screw 65 on a washer 66, and the pawl 61 is held in engagement with one of the teeth of the wheel 60 by means of a spring 67 fixed on the fore face of the gear wheel 63. On the rear face of the plate 2 is also fixed by means of a screw 68 a support 69 which fixedly holds a horizontal 45 threaded spindle 70 on which is idle a bushing 71 carrying two cylindrical gear wheels, one little 72 meshing with the gear wheel 63 and a bigger one 73 meshing with the little gear wheel 16 on the horizontal shaft 14. 50

In view of the above explained structure, when by virtue of the descending movement of the oscillatable frame 36 carrying along with it the metal strip 29 and the cam boss 28, the latter causes the pawl 25 to withdraw from the rack 24 and releases the heavy weight 21 for descending by gravity sliding on its guide 23, the rack 56 causes to rotate very slowly on its shaft 59 the idle bushing 58 carrying the wheels 57 and 60 in the direction indicated by the arrow in Figs. 14 and 15, whereupon the wheel 63 is caused to rotate also in the same direction through the medium of the pawl 61 engaging one of the teeth of the wheel 60, and this movement of wheel 63 causes rotation of the bushing 71 carrying the wheels 72 and 73 in the direction indicated by the arrow in said Figures 14 and 15. 65

Since the gear wheel 73 meshes fixedly with the gear wheel 16 of shaft 14, two cases may occur: firstly, when the gear pinion 12 does not mesh with the gear wheel 13 of the shaft 14, which occurs in the limit lowest position of the oscillating frame 36, then the gear pinion 52 of the counter-shaft 51 meshes with said gear wheel 13 and in this way the escapement contained

in the housing 55 is put in action to control the rotation of the time indicating shaft 18 which receives its motion from the shaft 14 through the medium of the gear pinion 15 and the gear wheel 17 fixed on said shaft 18; and in the second case when the gear pinion 12 meshes with the gear wheel 13 of the shaft 14, the time indicating shaft 18 rotates in the same direction by the motion transmitted from the shaft 5 of the electric motor 4, but upon the heavy weight 21 being in retained position, the system of gear wheels 72 and 73 is caused to rotate idly on the spindle 70 by the gear wheel 16 on the shaft 14 receiving its motion from the shaft 5 of electric motor 4 as already explained, but even though the gear wheel 72 cause to rotate the gear wheel 63 with which it meshes, such rotation will not produce any motion at all in the system of gear wheels 60 and 57, due to that the gear wheel 63 will rotate idly on its spindle and upon it carrying along the pawl 61, the latter will slide on the teeth of the ratchet wheel 60 by virtue of the oblique direction of the teeth.

Really, the use of the complicated gear system constituted by gear wheels 57 to 73 is due to the division of movement that is necessary in order to accomplish the longest possible period of time in the downfall of the heavy block 21 along a predetermined height, thence in the drawing is shown a gear system from wheel 57 to wheel 73 which is proper to cause the heavy block 21 to descend during a time of about six hours during which the supply of current to impulse the electric motor 4 may be interrupted, but anyone skilled in the art may assume that if the heavy block 21 is desired to run the whole slide distance in only half an hour for instance, the gear system may be limited to a single wheel or two wheels.

In Figs. 6, 15, 16 and 17 is shown a mechanism whose function is to cause the heavy weight 21 gradually to move back to its initial raised position, when upon having reached a low position, it is held in that fallen position by the pawl 25 when the oscillatable frame 36 is again raised by the attraction of the electromagnet 42 on its armature 41 pivotally connected with said oscillatable frame 36, upon electric current flowing again in the electric line 43—44 supplying the electric motor 4. Said mechanism is composed of a lever 74 which is pivotally mounted by a horizontal pin 75 on a plain member 76 which in turn is pivoted by a pin 77 at a small angle with the vertical on an angular support 78 slightly obliquely fixed by means of a screw 79 on the inner face of plate 2, whereby the lever 74 may effect two pivotal movements, at a time, one vertically about the pivot 75 and another substantially horizontal about the pivot 77. The lever 74 is pivotally connected at its end adjacent the vertical strip 29 and by means of a horizontal pin 80 with an arm 81 ending in a pawl of bevelled end face 82 and the arm 81 is maintained as forming a straight extension of the lever 74 in the raised position of the pawl 82 through the medium of a lower pin 23 laterally projecting from a lug 84 projecting downward from the adjacent end of the lever 74, said lug 84 being connected at a point 85 to a coil spring 86 whose other end is secured to a fixed point 87 of the plate 2.

The arm 81 extends until the pawl 82 is in vertical alignment with a series of pins 88 projecting horizontally from the front of the heavy weight 21 laterally to the rack 24 and equally spaced from each other. The lever 74 is operated

at like times by two rollers 89 rotatably mounted on the ends of two radial arms 90 fixed in opposite directions on the time marking shaft 18 which, if it is the horary shaft, every half hour will raise the arm 81 carrying the pawl 82 and cause the latter to engage a pin 88 and thereby the heavy weight 21 to ascend a space equal to the vertical distance between two pins 88 at the end of which ascending movement the weight 21 rests suspended by the pawl 25 constantly engaging the rack 24. Upon releasing each roller 89 the lever 74, the latter is restored to its normal position by the action of the spring 86 and during the ascending movement of the weight 21, the pawl 82, upon leaving one pin 88, passes clear along the inner side of the immediate lower pin 88 without striking against same in virtue of the oblique bevelled cut on its end face 82', and thus it is rendered in position to engage and raise the immediate lower pin 88 when the next roller 89 engages the lever 74 and operates it to raise the arm 81 again. In this movement, the outward swinging of the lever 74 on the pivot 77 is limited by the pressure exerted thereon by a curved spring 91 which at its lower end is fixed by screws 92 to the plate 2. The descending movement of the lever 74 and arm 81 is limited by two pins 93 and 94 fixed to the plate 2 (Fig. 4).

In the lower position of the oscillatable frame 36, in order that the arm 81 and pawl 82 may not hinder the descending movement of the weight 21, it is necessary to leave the pawl 82 out of the vertical course of the pin 88, and for that purpose the vertical strip 29 is provided at a suitable height thereon with an arched cam stop 95 projecting upwards from a point 96 on the strip 29, which stop 95 engages the arm 81 as the strip 29 descends and forces the arm to deviate outward together with the lever 74 and causes the latter to rotate on its pivot 77.

The operation of the electric clock provided with the improvements above described, is as follows: In the normal operating conditions, that is, when the electric motor 4 receives the electric current operating it from the current supply line 43—44, the shaft 5 of the motor transmits its motion to the time indicating shaft 18 through the gearing system 6, 7, 8, 9, 12, 13, 15 and 17, and the oscillatable frame 36 is then in raised position in virtue of the attraction exerted by the electromagnet 42 receiving current from the line 43—44, on its armature 41 connected as above described to the oscillatable frame 36 and, therefore, the gear pinion 52 being separated from the gear wheel 13, the clock escapement mechanism 55 of the casing 55 is inoperative, while the rotation of the shaft 14 which actuates the gearing mechanism 73, 72, and 63 does not produce any action at all on the gear mechanism 60, 57, 56, owing to the fact that the pawl 61 of the wheel 63 slides on the teeth of the wheel 60 without operating it, and the heavy weight 21 is securely maintained in its raised position by the pawl 25 which fixedly engages the rack 24.

When by any reason the flow of current in the supply line 43—44 fails, the electric motor 4 stops, the armature 41 of the electromagnet 42 is released and falls by gravity and carries along with it the oscillatable frame 36 whose fall produces three simultaneous operations: firstly, the spring 47 will engage the rear end of the shaft 11 and push it onwards against the fore spring 48, whereupon the gear pinion 12 will travel a certain distance and will be disengaged from the gear wheel 13; secondly, the shaft 51 will descend

until the gear pinion 52 engages the gear wheel 13 and the gear wheel 53 carried by said shaft 51 engages the small gear wheel 54 of the clock escapement mechanism housed in the casing 55; 5 and ultimately, the strip 29 will descend, whereupon the cam boss 28 formed thereon will engage the spring 26 and the pawl 25 of the latter will be disengaged from the rack 24, after which the heavy weight 21 will be free to fall by gravity.

10 Upon the weight 21 being released, the side rack 24 thereof will actuate upon the idle gear wheel 57 causing it to rotate in the direction indicated by the arrow in Fig. 12, whereupon the wheel 60 will also rotate in the same direction through the medium of the idle bushing 58 and the wheel 60 will carry with it the gear wheel 63 through the medium of the pawl 61, thus giving the wheel system 72, 73, 16 and 13 the rotation which was formerly given from the electric motor 4 by the meshing of gear pinion 12 with gear wheel 13, whereby the rotation of the time indicating shaft 18 will not be interrupted and the rotation time of this shaft will be controlled by the clock escapement mechanism inclosed in the casing 55.

15 When the heavy weight 21 is in a fallen position and electric current flows again through the circuit 43—44 supplying the electric motor 4, the current flows along the coil of electromagnet 42 and the armature 42 thereof is drawn up 20 immediately, whereupon the oscillatable frame 36 ascends and three operations are effected which are inverse to those described above, that is: in the first place, as the spring 47 ascends with the frame 36, it releases the rear end of the shaft 11, 25 whereupon the fore spring 48 actuates by its own resiliency and pushes the shaft 11 backward, again causing the gear pinion 12 to engage the gear wheel 13; in the second place, the counter-shaft 51 ascends together with the frame 36 and 30 thereby the gear pinion 52 is disengaged from the gear wheel 13 and the gear wheel 53 is disengaged from the gear wheel 54 of the escapement mechanism inclosed in casing 55, in virtue of which the escapement mechanism will remain inoperative; and in the third place, upon the strip 29 ascending with the oscillatable frame 36, the cam boss 28 thereof will release the spring 29 and the pawl 25 of the latter will again engage one of the teeth of the rack 24, to fix the weight 21 in 35 position. In these conditions, the operation of the gear wheels system 57 and 60 will be stopped, but the wheel 63 will continue to move idly on its spindle 59 by virtue of the motion transmitted to it from the shaft 5 of the electric motor 4 through the gear wheels and pinions 6, 7, 8, 9, 40 12, 13, 16, 17, 18, and the pawl 61 will slide on the teeth of the wheel 60 without actuating the latter, whereupon the time indicating shaft 18 will receive its motion direct from the shaft 5 of the electric motor 4. Furthermore, in continuing the movement of the time indicating shaft 18, if this is the hour indicating axis, the two rollers 89 will alternately engage every half hour the lever 74 causing its rear portion to descend 45 and the arm 81 to ascend until the pawl 82 thereof engages one of the pins 88 and upon pushing this pin upward it will cause the weight 21 to ascend a determined distance at the end of which the weight will be held by the pawl 25 50 and the arm 81 to descend until the pawl 82 thereof engages one of the pins 88 and upon pushing this pin upward it will cause the weight 21 to ascend a determined distance at the end of which the weight will be held by the pawl 25 55 and the arm 81 to descend until the pawl 82 thereof engages one of the pins 88 and upon pushing this pin upward it will cause the weight 21 to ascend a determined distance at the end of which the weight will be held by the pawl 25 60 and the arm 81 to descend until the pawl 82 thereof engages one of the pins 88 and upon pushing this pin upward it will cause the weight 21 to ascend a determined distance at the end of which the weight will be held by the pawl 25 65 and the arm 81 to descend until the pawl 82 thereof engages one of the pins 88 and upon pushing this pin upward it will cause the weight 21 to ascend a determined distance at the end of which the weight will be held by the pawl 25 70 and the arm 81 to descend until the pawl 82 thereof engages one of the pins 88 and upon pushing this pin upward it will cause the weight 21 to ascend a determined distance at the end of which the weight will be held by the pawl 25 75

It is obvious that the construction details and the shape of the structure above described may be varied, without by this reason it may be considered as altered the essential character of the invention which is such as claimed hereinafter. 5

What I claim is:

1. In an electric clock, a time indicating shaft, an electric circuit adapted to be connected to a source of current, an electric motor in said circuit, a train of gears for operating the time indicating shaft from the motor, electromagnetic means in said circuit including an armature, vertically oscillatable means secured to said armature, gravity actuated means releasably connected to said oscillatable means upon de-energization 15 of the electromagnetic means upon failure of current, ratchet means for drivingly connecting the gravity actuated means to one of the gears of the gear train of the electric clock, a clock escapement, and gear means on the oscillatable 20 means for driving the clock escapement from one of the gears of the gear train, whereby the clock is driven by the gravity actuated means and its motion controlled by the escapement upon failure 25 of the current.

2. In an electric clock, a clock frame, a time indicating shaft, an electric circuit adapted to be connected to a source of current, an electric motor in said circuit, a train of shafts and gears for operating the time indicating shaft from the 30 motor, means on the clock frame for slidably mounting one of the shafts of said shaft and gear train along its axial line, electromagnetic means in said circuit including an armature, vertically oscillatable means secured to said armature, resilient means secured to the vertically oscillatable means for disconnecting the slidable shaft of said shaft and gear train from the electric motor, gravity actuated means releasably connected to said oscillatable means upon de-energization 35 of the electromagnetic means upon failure of current, ratchet means for drivingly connecting the gravity actuated means to the slidable shaft of said shaft and gear train, a clock escapement on the clock frame, and gear means 40 on the oscillatable means for driving the clock escapement from the slidable shaft of said shaft and gear train, whereby the clock is driven by the gravity actuated means and its motion controlled by the escapement upon failure of the current. 45

3. In an electric clock, a clock frame, a time indicating shaft, an electric circuit adapted to be connected to a source of current, an electric motor in said circuit, a train of shafts and gears for operating the time indicating shaft from the motor, an angular arm secured on the clock frame for slidably mounting one of the shafts of said shaft and gear train along its axial line, electromagnetic means in said circuit including an 50 armature, a vertically oscillatable frame secured to said armature, a spring secured to said oscillatable frame for engaging and sliding the slidable shaft of said shaft and gear train, a spring secured to the clock frame for backing said slid- 55 able shaft upon release by the first mentioned spring, gravity actuated means releasably connected to said oscillatable frame upon de-energization of the electromagnetic means upon failure of current, ratchet means for drivingly connecting the gravity actuated means to the slid- 60 able shaft of said shaft and gear train, a clock escapement on the clock frame, and gear means on the oscillatable frame for driving the clock escapement from the slidable shaft of said shaft 65 70 75 80 85 90

and gear train, whereby the clock is driven by the gravity actuated means and its motion controlled by the escapement upon failure of the current.

- 5 4. In an electric clock, a clock frame, a time indicating shaft, an electric circuit adapted to be connected to a source of current, an electric motor in said circuit, a train of shafts and gears for operating the time indicating shaft from the 10 motor, means on the clock frame for slidably mounting one of the shafts of said shaft and gear train along its axial line, electromagnetic means in said circuit including an armature, a vertically oscillatable frame secured to said armature, a weight slidably supported on the clock frame and releasably connected to said oscillatable frame upon de-energization of the electromagnetic means upon failure of current, ratchet means for drivingly connecting the weight to the 15 slidable shaft of said shaft and gear train, a series of pins projecting from the weight and spaced 10 apart in vertical alignment, lever means pivotally supported on the clock frame, a pawl pivotally connected to one end of said lever means and adapted to releasably engage a pin on the weight, spring means connecting the pivotally connected 20 end of said lever means to the clock frame, a pair of diametrically opposed radial arms on the time indicating shaft, and rollers rotatably mounted on the ends of said radial arms and adapted to engage the free end of said lever 25 means, whereby the clock is driven by the weight in falling upon failure of current and upon resumption of the current the clock itself will automatically return the fallen weight to its initial fully raised position.

- 30 5. In an electric clock, a clock frame, a time indicating shaft, an electric circuit adapted to be

connected to a source of current, an electric motor in said circuit, a train of shafts and gears for operating the time indicating shaft from the motor, means on the clock frame for slidably mounting one of the shafts of said shaft and gear train along its axial line, electromagnetic means in said circuit including an armature, a vertically oscillatable frame secured to said armature, a weight slidably supported on the clock frame and releasably connected to said oscillatable frame upon de-energization of the electromagnetic means upon failure of current, ratchet means for drivingly connecting the weight to the 10 slidable shaft of said shaft and gear train, a series of pins projecting from the weight and spaced 15 apart in vertical alignment, lever means pivotally supported on the clock frame, a pawl pivotally connected to one end of said lever means and adapted to releasably engage a pin on the weight, spring means connecting the pivotally connected 20 end of said lever means to the clock frame, a pair of diametrically opposed radial arms on the time indicating shaft, and rollers rotatably mounted on the ends of said radial arms and adapted to engage the free end of said lever 25 means, whereby the clock is driven by the weight in falling upon failure of current and upon resumption of the current the clock itself will automatically return the fallen weight to its initial fully raised position.

JOSÉ ANDRÉS HERNANDEZ.
